BURNER COMPARTMENT CLOSURE

George D. Wilkinson, Oak Park, and Elmer D. Pellegrin, Des Plaines, Ill., assignors to Cribben & Sexton Company, Chicago, Ill., a corporation of Illinois

Application January 12, 1933, Serial No. 651,400

5 Claims. (Cl. 126—39)

This invention relates to a burner compartment closure and is particularly useful in connection with closure means for the burner compartment of a gas range.

5 An object of the invention is to provide closure means which effectively conceals the interior of a burner compartment but which may be readily opened to provide access to the compartment without removing the handles of the burner valves and of other instruments. Another object is to provide readily removable means for locking the closure in shut position. A further object is to provide a hinged door for closing the burner compartment, the door itself being readily removable not only from its shielding position but also from its connections with the range frame. Other specific objects and advantages will appear as the specification proceeds.

20 The invention is illustrated, in a preferred embodiment, by the accompanying drawing, in which—

Fig. 1 is a broken front view in elevation of a portion of a range embodying my invention, the door to the burner compartment being closed; 25 Fig. 2, a view similar to Fig. 1, the door being in open position; Fig. 3, a broken enlarged sectional view, the section being taken as indicated at line 3 of Fig. 2; Fig. 4, an enlarged detail view of the valve stem for the oven burner; and Fig. 5, a 30 sectional view of the removable handle for the valve stem shown in Fig. 4.

In the illustration given, A designates a gas range affording a gas burner compartment A'; and B designates a hinged door adapted to close the compartment A'.

The range A may be of any suitable construction. Because of the well known construction of the type of range illustrated, it is believed unnecessary to set forth the construction in detail. 40 Within the burner compartment A' is supported a gas manifold 10 and above the manifold are located burner pipes 11 from which extend outwardly the burner handles 12. The burner handles 12 are employed to control the gas fed to the burners (not shown) directly above the compartment A'. Below the manifold 10 is located the gas pipe 13 leading to the burner within the oven. The pipe 13 is provided with a valve stem 14 having a forward portion cut away at 15, as shown more clearly in Fig. 4. The handle 16, as shown more clearly in Fig. 5, is provided with a recess 17 in which is secured a metal lining 18 adapted to receive the cut-away end of the stem 14. The metal insert 18 is provided with an open-

ing or socket 18^a adapted to receive the spring urged plunger 18^b with which the stem 14 is provided. Preferably, the handle 16 is formed of a composition product, such as for example a phenolic condensation product known as bakelite, and the recess therein is designed to form a tight fit with the end of valve stem 14. The spring plunger 18^b serves to releasably lock the handle on stem 14.

Below the handle 16, is located a heat regulator 19 for the oven and the heat regulator handle or knob 20 extends forwardly from the instrument 19.

The closure B may also be of any suitable construction. We prefer, however, to form the closure plate or door as illustrated more clearly in Figs. 2 and 3 the border portions of the plate being turned inwardly to form flanges 21. In the illustration given, the door B is pivotally connected at one end to the range frame. Secured to the range frame are a pair of spaced angle irons 22 and 23. Secured to the upper member 22 is a relatively long pin 24 and to the lower member 23, a relatively short pin 25 (see Fig. 3). The top and bottom flanges 21 are perforated at 26 to receive the pins 24 and 25. With the construction illustrated, the door B may be removed by raising the door until the short pin 25 is clear and then lowering the door so as to allow the pin 24 to clear the recess 26 of the top flange 21. In assembling the door, the steps are reversed. As shown more clearly in Figs. 1 and 2, the door B is provided near its top with a longitudinal slot 27 adapted to receive the handles 12. Also, the door is provided near its bottom with a circular opening 28 adapted to receive the handle or knob 20 of the heat-regulator. Between the openings 27 and 28, is a relatively small opening 29 adapted to receive the hub portion 30 of the oven-burner handle 16.

In the operation of the device, when it is desired to open the door B, the oven-burner handle 16 may be drawn forward with sufficient force to release its grip upon the valve stem 14. With the handle 16 removed, the door B may be swung to the position illustrated in Fig. 2, the slot or longitudinal opening 27 permitting the door to pass by handles 12, and the opening 28 permitting the door to pass by the handle or knob 20. The burner compartment is now open for cleaning or for repair of the parts. If it is desired to remove the door B from its hinges, the door may be simply raised to clear the pivot pin 25 and then dropped to clear the pivot pin 24. In the assembly of the apparatus, the door may be readily placed in po-

sition by first passing the pin 24 through the opening 26 in the top flange 21, and then dropping the door so that the opening 26 in the lower flange 21 receives the short pin 25. In the removal or in the assembly of the door B, the longitudinal opening 27 affords a handle by which the operation can be readily carried out.

When the door B is moved to closed position, past the handles 12 and 20, the door may be 10 locked in this position by pressing the handle 16 upon the valve stem 14.

While, in the illustration given, we have shown particular forms of handles and correspondingly-shaped openings in the door B, it will be understood that the character and shapes of the handles and also of the openings in the door B may be modified greatly without departing from our invention. The foregoing detailed description has been given for clearness of understanding 20 only, and no unnecessary limitations should be understood therefrom, but the appended claims should be construed as broadly as permissible, in view of the prior art.

We claim:

- 25 1. In combination with a range having a burner compartment and instrument handles extending therefrom, a valve stem equipped with a removable handle also extending therefrom, and a door hingedly connected to the range and having an opening through which said first mentioned handles extend to a point beyond the door as the door is closed and having also a small opening adapted to receive the valve stem therethrough when the same is not equipped with the 30 removable handle.
2. In combination with a range having a burner compartment and a plurality of burner handles extending therefrom, a valve stem also extending therefrom and having a portion of its 35 end cut away, a handle provided with a recess adapted to form a sliding fit with the end of said valve stem, and a door hingedly connected on one side with the range frame, said door having an opening adapted to receive said first mentioned

handles and having also an opening adapted to receive said valve stem when its handle has been removed.

3. In combination with a range having a burner compartment and a plurality of burner valve stems extending therefrom, a removable panel closing the front of said burner compartment and provided with an opening adapted to receive some of said valve stems, said panel also being provided with a small opening adapted to receive at least 10 one of said valve stems, valve handles secured to the stems extending through said first-mentioned opening and adapted to be received therethrough when the panel is removed, and a removable handle releasably engaging the end of said valve 15 stem extending through said last-mentioned opening and adapted to releasably lock said panel in closed position.

4. In combination with a range having a burner compartment and a plurality of valve stems extending therefrom, a removable burner panel substantially flush with the front wall of said range and closing said burner compartment, said panel being provided with an opening through which said valve stems extend, handles secured 20 to the ends of said valve stems and adapted to engage the front of said panel to prevent its removal when said handles are turned in one direction but adapted to be received through said opening to permit the removal of the panel when 25 the handles are turned in another direction.

5. In combination with a range having a burner compartment and a plurality of burner valve stems extending therefrom, a removable panel closing the front of said burner compartment 30 and arranged substantially flush with the front wall of said range, said panel being provided with an opening through which said valve stems extend, valve handles secured to the ends of said stems and receivable through said opening only 40 when the handles are turned in one direction.
